UNITED STATES PATENT OFFICE.

CHARLES A. LINDSTRÖM, OF ALLEGHENY, PENNSYLVANIA, ASSIGNOR TO
PRESSED STEEL CAR COMPANY, OF MCKEES ROCKS, PENNSYLVANIA, A
CORPORATION OF NEW JERSEY.

CARLINE FOR RAILWAY-CARS.

No. 845,961.

Specification of Letters Patent.

Patented March 5, 1907.

Application filed December 8, 1905. Serial No. 290,884.

To all whom it may concern:

Be it known that I, CHARLES A. LINDSTRÖM, of Allegheny, Allegheny county, Pennsylvania, have invented a new and useful Improvement in Carlines for Railway-Cars, of which the following is a full, clear, and exact description, reference being had to the accompanying drawings, forming part of this specification, in which—

10. Figure 1 is a side elevation showing my improved carline in position. Fig. 2 is a bottom plan view; and Figs. 3 and 4 are cross-sections on the lines III III and IV IV, respectively, of Fig. 1.

15. My invention relates to metal carlines for railway-cars, and is designed to provide an improved form of carline which will avoid cutting through of the car side to receive the end of the carline.

20. In the drawings the carline, which is preferably of trough shape in cross-section, consists of a web portion 2 and vertical flanges 3. These flanges 3 are preferably bent upwardly at their ends, as shown at 3', and the web 2 is preferably narrowed, as shown at 2', giving the shape of Fig. 4 at the ends. They are also preferably turned outwardly at their lower edges, as shown at 3", forming inclined lips, which materially increase the strength of 30 the carline and which will not retain any of the lading with which the car may be loaded. The provision of these flanges also enables the edges of the carline to be trimmed after the pockets or recesses for the purlins, hereinafter referred to, are pressed in the carline. Such pressing distorts the lower edges of the carline, and these edges are difficult to trim when the two sides of the carline are parallel.

25. The end portions of the carline are bent or curved upwardly from the point a and thence extend downwardly and outwardly substantially in line with the main portion of the carline. The side plate 4 may be recessed slightly at its upper edge to receive the thickness of the end portion of the carline, which thus avoids cutting the side plate to an undesirable depth.

30. The web portion 2 of the carline preferably terminates at the outer edge of the side plate; but the flanges 3' extend beyond the

web and are bent vertically down, so as to fit against the outer face of the side plates, as shown in Figs. 1 and 2. These flanges may be secured to the side plate by any suitable means, such as the bolts 5. The vertical flanges of the carline hold the sides of the car together independently of the bolts, so that the carlines are much more efficient in strengthening the frame than in the form heretofore used. I have shown the purlins 6 as resting in depressions 7, pressed in the top of the carline, for this purpose; but these purlins may be supported or secured in any desirable manner.

35. The advantages of my invention result particularly where purlins of considerable depth are employed. If the purlins are shallow, the carline may rest in vertical recesses in the side plates; but if the purlins are deep these cuts become objectionable, and the bending of the carline as above shown and described avoids this difficulty.

40. Many variations may be made in the form and arrangement of the carline, side plates, purlins, &c., without departing from my invention.

I claim—

1. A carline having its end portions bent or curved upwardly and thence outwardly to rest on the side plates; substantially as described.

2. A carline having its end portions bent or curved upwardly and thence extending outwardly and downwardly to rest on the side plates; substantially as described.

3. A carline having its end portion curved or bent upwardly and thence outwardly, the end having a downturned portion arranged to embrace the outer face of the side plate; substantially as described.

4. A carline of trough shape in cross-section having its end portions bent or curved upwardly and thence extending outwardly, the flange portions of the shape having lateral lips which are bent downwardly at the ends to embrace the side plates; substantially as described.

5. In car construction a metal carline and purlins resting on its intermediate portion, the end portion of the carline being bent or

curved upwardly, and thence extending outwardly and downwardly in substantially the top plane of the purlin and resting on the car side; substantially as described.

5 6. A carline of trough shape in cross-section, having its end portions bent or curved upwardly, and thence outwardly, and also having outwardly-bent lips at the lower edge

portions of its webs or flanges; substantially as described.

In testimony whereof I have hereunto set my hand.

CHARLES A. LINDSTRÖM.
